UNITED STATES PATENT OFFICE.

CHARLES S. JOHNSON, OF DETROIT, MICHIGAN.

BOOK-SUPPORT ATTACHMENT FOR DESKS AND THE LIKE.

Application filed July 14, 1924. Serial No. 725,988.

This invention relates generally to stands having movable arms for supporting books, music, periodicals and other articles, and refers more particularly to stands of this type which may be readily attached to desks or other articles of furniture so that the books, etc., may be swung over the top of the desk to a convenient position for use by a person seated at the desk.

One of the essential objects of the invention is to provide a stand of this type that may be easily and quickly attached to or removed from a desk or other standard article of furniture without marring the same.

Another object is to provide simple and effective means for attaching the stand to the desk so that the weight of the desk may be utilized instead of a heavy base for the stand to prevent the latter from tipping over when a heavy book or other article is placed upon the supporting arm of the stand.

A further object is to provide means for preventing the stand from turning on the floor relative to the desk when the latter is moved for any reason.

Still another object is to provide a strong and durable stand that is simple in construction and that can be manufactured at comparatively low cost.

With the above and other objects in view the invention consists in certain novel features of construction, combination and arrangement of parts as will be more fully described and particularly pointed out in the appended claims.

In the accompanying drawings:—

Figure 1 is a perspective view of a stand embodying my invention attached to a flat top desk;

Figure 2 is a vertical sectional view through the stand;

Figure 3 is a top plan view of the stand.

Figure 4 is a side elevation of the stand.

Figure 5 is a sectional view taken on the line 5—5 of Figure 3.

Figure 6 is a sectional view through the horizontal arms and showing the holder and adjusting screw in elevation.

Figure 7 is a perspective view of a slight modification.

Figure 8 is an enlarged detail elevation

of the ball race supporting the arms shown in Figure 7.

Figure 9 is a sectional view taken on the line 9—9 of Figure 7.

Figure 10 is a sectional view taken on the plane indicated by the line 10—10 of Figure 7.

Referring now to the drawings in which like characters of reference designate corresponding parts throughout the several views, the numeral 1 designates a stand embodying my invention having a horizontal frame 2 upon which the supporting standard 3 for the horizontal arm 4 is preferably mounted.

To facilitate the assembly, the frame 2 is preferably formed of suitable tubes or pipes which may be connected together by any suitable means. As shown, the tubes 5 are preferably bent intermediate their ends to provide the complementary leg portions 6 and the upright sections 7 of the standard 3, while the tube 8 is preferably bent at its opposite ends to provide the leg portions 9. A suitable tube 10 is secured to the leg portions of the tubes 6, while suitable tubes 11 are preferably connected at their opposite ends to the leg portions 6 and 9 respectively of the tubes 5 and 8 to brace and reinforce the same.

In order that the arm 4 may be swung freely about the standard 3 and at the same time will have a positive support, I preferably provide suitable metal castings 13 and 14 that are mounted upon the upright sections 7 of the standard 3 as shown in Figure 2 of the drawing. The casting 13 is provided with a central opening 15 for receiving the vertical pivot portion 16 of the arm 4 and has depending lugs 17 which fit snugly within the upper ends of the upright sections 7 of the standard. The casting 14 is preferably sleeved upon the sections 7 at the lower ends thereof and is provided intermediate its ends with a tapered socket 18 which forms a bearing for the tapered lower end of the vertical pivot portion 16 of the arm 4. Any suitable means may be mounted on the horizontal arm 4 for supporting articles of different kinds. As shown, I preferably provide a suitable holder 19 for books,

catalogues, music and the like, having a central stud 20 that preferably extends through a suitable boss 21 at the free end of the arm 4 and is clamped in position by means of a suitable winged nut 22 threadedly engaging the stud 20 below the arm 4. Thus, with this construction, the arm 4 may be readily swung over a suitable flat top desk 23 for supporting books, etc., in a convenient position for use by a person seated at the desk. Any suitable means such as a set screw 26 threadedly engaging the casting 13 may be employed for holding the arm 4 in adjusted position.

15 In order that the arm 4 may be raised or lowered as desired above the top of the desk, the casting 14 is preferably adapted to be moved vertically upon the sections 7 of the standard and may be held in an adjusted 20 position by means of suitable set screws 25.

25 In order that the weight of the desk may be utilized for preventing the stand from tipping over when a catalogue or other heavy article is placed on the holder 19, I preferably provide a horizontal bearing plate 27 for taking the pressure at the bottom of the desk. As shown, the plate 27 is preferably formed of two telescopically engaging sections 28 and 29 respectively, having upstanding flanges 30 at their outer ends for clamping engagement with the sides of the drawer receiving end portion 31 of the desk. If desired, suitable felt pads 32 may be secured to the inner faces of the flanges 30 to prevent the latter from marring the desk. Any suitable means such as a bolt 33 may be used to adjust the sections 28 and 29 respectively of the plate 27. As shown, this bolt extends freely from a depending lug 34 on the section 29 and threadedly engages a depending lug 35 on the section 28. Thus, the clamping engagement with the desk may be easily and quickly effected by merely rotating the bolt 33.

45 For preventing the frame 2 from turning relative to the desk when the latter is moved for any reason, I preferably provide three vertical bolts 39 that are carried by the frame 2 and are adapted to engage suitable 50 sockets 40 projecting downwardly from the sections 28 and 29 respectively of the bearing plate at the outer free ends thereof. As shown, two of the bolts 39 threadedly engage an arm 40^a that is slidably mounted on parallel rods 41 extending between the tubes 6 and 8 respectively at the opposite ends of the frame, while the third bolt 39 preferably engages an enlargement 42 at the outer end of a horizontal arm 43 projecting laterally 55 from an arm 44 that is slidably mounted on the parallel rods 41. Thus, with this construction, the arms 40 and 44 may be readily adjusted on the parallel rods 41 to accommodate drawer receiving portions of different widths and to permit the stand to be

60 moved out or in with respect to the desk according to the distance the top of the desk projects over the end walls thereof.

65 In order that the stand may be raised or lowered with respect to the desk when necessary, I preferably provide suitable feet 45 which threadedly engage the lower ends of the leg portions 6 and 9 respectively of the tubes 5 and 8. Thus, any one of these feet 70 may be adjusted with respect to the leg portion to which it is connected to take care of any uneven floor, rug or other surface upon 75 which the stand is placed.

80 From the foregoing description it will be readily apparent that I have provided a very light and durable stand that may be readily attached to a desk or other standard article of furniture without marring the same. Hence, the use of securing elements such as 85 nails, bolts, screws, etc. which permanently disfigure the furniture is obviated entirely. Moreover, the form of attachment is such that the weight of the desk is utilized to prevent the stand from tipping over, consequently it is not necessary to provide the 90 stand with a heavy and cumbersome base. Another important feature is the provision of the vertical bolts 39 which are engageable 95 with the sockets 40 projecting downwardly from the sections 28 and 29 respectively of the bearing plate 27 to prevent the frame and standard from turning relative to the desk when the latter is moved for any reason. Furthermore, it will be apparent that the 100 stand may be readily attached to the drawer receiving portions of desks and other articles of furniture of different widths, inasmuch as the bearing plate is formed of telescoping sections which may be adjusted as 105 desired.

110 Inasmuch as the casting 14 is sleeved upon the vertical sections 7 of the standard 3, it is also readily apparent that the bearing 115 18 for the vertical portion 16 of the arm may be adjusted vertically so that the arm 4 may be raised or lowered as desired above the top of the desk. Another important feature is the provision of the adjustable feet 45 which permit the stand as a unit to be raised or lowered as desired.

120 In Figures 7 to 9 inclusive of the drawings I have provided a slight modification in which the frame 50 of the stand is preferably formed of two iron castings 51 and 52 respectively and the spaced longitudinally extending rods 53. With this construction, the standard 54 is preferably formed of two spaced tubes 55 which are threaded into the horizontal portion 56 of the end casting 51 of the frame and are connected at their upper ends by a cross bar 57 which is provided at its opposite ends with depending lugs 58 which fit snugly within the upper ends of the tubes 55.

125 In order that the horizontal arm 59 for 130

supporting a holder (not shown) may be swung freely over the top of the desk, the vertical pivot portion 61 of the arm preferably extends downwardly through the cross bar 57 and is provided with an annular flange 62 that rests upon a suitable ball race 63 mounted on the cross bar 57. Thus with this construction, the sectional bearing plate 65 is preferably slidable vertically on the tubes 55 of the standard and is adapted to be held in adjusted position against the drawer receiving portion of the desk by means of a single adjusting screw 66 which preferably threadedly engages the upwardly projecting inverted substantially U-shaped portion 67 of the end casting 52 of the frame. As shown, the section 68 of the plate is preferably provided at its outer end with a lateral extension 69 having spaced bosses 70 which receive the tubes 55 of the standard and are adapted to slidably engage the same. The extension 69 of the section 68 is also provided with an intermediate boss 71 that receives the vertical pivot portion 61 of the arm 59 and slidably engages the same. Thus the engagement of the bosses 70 with the tubes 55 will effectively prevent the frame 50 from turning relative to the desk when the latter is moved for any reason. Inasmuch as the rods 53 threadedly engage the castings 51 and 52, it is also readily apparent that the frame may be readily knocked down for shipping or storing purposes.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim as my invention is:

1. A stand for use with a desk having a frame located beneath the desk, a standard substantially rigidly mounted on the frame, a supporting arm carried by a member adjustably mounted upon the standard, and means for utilizing the weight of the desk for preventing the stand from tipping over, said means including a sectional plate clamped to a portion of the desk, and means carried by the frame for adjusting said plate upwardly against said desk and into contact with vertical portions thereof, and means for adjusting the sections of the plate to fit the desk.

2. A stand for use with a desk having a frame located beneath the desk, a standard mounted on the frame, a supporting arm carried by the standard, and means for utilizing the weight of the desk for preventing the stand from tipping over, said means including a sectional plate, means for clamping said plate to a portion of the desk, and

means carried by the frame for adjusting the plate upwardly into engagement with the desk and preventing the frame from moving relative to the desk when the latter is moved.

3. In a stand, a frame comprising a standard having spaced substantially rigid vertical sections, a horizontal arm having a vertical pivot portion, and a foot bearing for the pivot portion of said arm carried by the spaced sections of the standard, and vertically adjustable on said sections.

4. A stand attachable to an article of furniture, comprising a base frame insertable beneath said article, a bearing member engageable with an under face of said article, means mounting said bearing member for vertical adjustment upon said base frame for clamping said frame between said under face of the article and a floor supporting the article for said frame, abutments carried by said bearing member engageable with opposite vertical faces of said article of furniture, means for adjusting said abutments for engaging them with or disengaging them from the article, an upright carried by said frame adapted to rise adjacent said article of furniture, and an arm pivoted upon the upper end of said upright to swing above said article of furniture.

5. A stand attachable to an article of furniture, comprising a base frame insertable beneath said article, a standard mounted on the frame, a supporting arm carried by the standard, means for utilizing the weight of the article for preventing the stand from tipping over, said means including a plate slidably mounted upon said frame and upwardly adjustable against a portion of the article.

6. A stand attachable to an article of furniture comprising a base frame insertable beneath the article, a standard mounted on the frame, a supporting arm carried by the standard, a plate comprising telescopically engaging sections clamped to a portion of the article, means carried by the frame for vertically adjusting said plate against the article, and means other than said first mentioned means for positively moving one of said telescopically engaging sections longitudinally of the other.

7. A stand attachable to an article of furniture, comprising a base frame insertable beneath the article, a standard mounted on the frame, a supporting arm carried by the standard, a plate slidably carried by the frame and comprising telescopically engaging sections terminating in upstanding flanges, means carried by the frame for adjusting said plate upwardly against the article, and means other than said first mentioned means for adjusting said telescopically engaging sections to bring said flanges into firm engagement with the sides of the article.

8. A stand attachable to an article comprising a base frame insertable beneath the article, a standard mounted upon the frame, a supporting arm carried by the standard, a bearing plate comprising relatively movable sections having bearing portions slidably mounted upon said frame and having verti-

cal portions engageable with opposite side walls of said article, and means for adjusting the sections upon said frame to bring the vertical portions aforesaid into firm engagement with the side walls of the article.

In testimony whereof I affix my signature.
CHARLES S. JOHNSON.
